CARBURETOR

Filed April 9, 1928

UNITED STATES PATENT OFFICE

WESLEY M. CROSS, OF DETROIT, MICHIGAN

CARBURETOR

Application filed April 9, 1928. Serial No. 268,514.

My invention relates to a new and useful improvement in a carburetor and has for its object the provision of a carburetor in which air is led into and in contact with fuel contained in the carburetor in liquid form and led after passing through the liquid into the engine with which used.

It is another object of the invention to provide a carburetor attached to an internal combustion engine in such a manner that the operation of the engine will set up a vacuum in the carburetor and draw air into contact with and through liquid fuel contained in the carburetor and serve to maintain through the vacuum a constant level of liquid fuel in the carburetor.

Another object of the invention is the provision in a carburetor of this class of an outlet delivery tube normally projecting into the liquid fuel.

Another object of the invention is the provision in a carburetor of this class having an outlet delivery pipe normally projecting into the liquid fuel of an air tube communicating with the atmosphere.

Another object of the invention is the provision in a carburetor free from floats of vacuum controlled means for maintaining a constant level of liquid fuel in the carburetor.

Other objects will appear hereinafter.

The invention consists in the combination and arrangement of parts hereinafter described and claimed.

The invention will be best understood from a reference to the accompanying drawings which form a part of this specification and in which,

Fig. 1 is a central vertical sectional view of the invention.

Fig. 2 is a side elevational view of the invention.

Fig. 3 is a sectional view taken on line 3—3 of Fig. 1.

Fig. 4 is a sectional view taken on line 4—4 of Fig. 1.

The invention comprises a reservoir or bowl 7. A neck 8 extends upwardly from the bowl 7 and is provided with a threaded flange 9 which threads into the open end of the bowl 7. Seated in the upper end of the neck 8 is a col-

lar 10 engaging in which is a sleeve 11 projected through which is the rockable rod 12 carrying the butterfly valve 13. A valve seat 14 is formed in the flange 9 engaging against which is the valve 15 projecting upwardly from which is a stem 16 extending through the coil spring 17 which engages at one end the flange 9 and at the other end a collar mounted fixedly on the stem 16.

A housing 18 provided with perforations 19 and closed with the cap 20 and 21 serves to shield the spring from dust, etc. The upper end of the stem 16 is provided with a ball whereby connection is made with the arm 22 which is fixedly attached to the rod 12. In the base 23 of the neck 8 there is threaded a nipple 26 projecting upwardly from which is the funnel 25. Threaded on the nipple 26 at the side of the base 23 opposite to the funnel 25 is a head 27 having tubular arms 29 radiating outwardly therefrom, each provided with a passage 28.

Threaded into the lower end of the head 27 and communicating therewith is a pipe 24 which extends below the normal level of the liquid fuel which is shown by the dotted line. The lower end of the pipe 24 is provided with a valve seat against which the needle valve 35 which is threaded through the base of the bowl 7 engages. Mounted on the lower surface of the base 23 and projecting inwardly of the bowl 7 is a conical shield 30 having its lower end open as at 31.

Projecting inwardly of the bowl 7 is a feed pipe 32 which extends through the flange 9 and connects to a delivery pipe 33.

Leading from the valve seat 14 below the normal fuel level and communicating with the interior of the housing 19 when the valve 15 is moved from its seat is a tube 34 which communicates at its lower end with a head 34' having a plurality of tubular arms 34" communicating therewith. Projecting laterally from one side of the neck 8 is a tubular projection 36, an opening being formed in the neck 8 to register with this projection 36. Threaded in the opening is a collar 37 having its inner face provided with a valve seat and adapted to be engaged by the valve head 38 which is mounted on the valve stem 100.

39 projecting inwardly of the sleeve 11, this sleeve serving as a guide for the movement of the valve 38. Mounted in the member 36 is a sleeve 40 which serves as a cylinder, this sleeve 40 being secured in the member 36 by set screws 41. Lateral openings 42 are formed in the sleeve 40, the outer end of the sleeve 40 being closed by a head 43 in which is formed the central opening 44. Slidably positioned in the sleeve 40 outwardly from the openings 42 is a piston 45 which is connected to the stem 39. Embracing the stem 39 is a sleeve 46 carrying the slotted drum 47, this drum having a plurality of slots or openings 48 formed therein. Springs 49 engage shoulders formed on the member 40 and the piston 45 to normally resist movement of the piston 45 in one direction so that these springs normally retain the valve 38 on its seat.

20 In operation, when the member 8 is connected to the intake manifold of an internal combustion engine and the delivery pipe 33 connected to a suitable source of fuel supply and the engine set in operation, a vacuum will be produced in the bowl 7. When the engine is idling this vacuum will draw upwardly in the tube 24 a small amount of liquid fuel which mixing with the air conducted to the pipe 24 by the pipe 57 will become vaporized.

When the engine is being operated for driving purposes, the butterfly valve 13 will be open and the valve 15 will be moved from its seat. The engine setting up a vacuum in the bowl 7 will draw through the feed pipe 32 sufficient liquid fuel until this fuel rises to the position shown by the dotted line 59 upon which, no further delivery of fuel into the bowl 7 will be effected as the vacuum cannot operate then through the pipe 32. When this vacuum is set up, air will be drawn through the pipe 34 and passed outwardly through the arms 34'', this air becoming saturated with the liquid fuel and passing outwardly through the passages 28 so as to be delivered to the engine for combustion purposes. As the carrying off of the liquid fuel by the saturated air lowers the level 59, further delivery of liquid fuel into the bowl 7 by the pipe 32 will be effected.

When the engine is run at high speed so that additional air is required, the suction set up in the member 8 by the engine will become great enough to move the valve 38 from its seat thus permitting the entry of the extra amount of air required.

In this way I have provided a carburetor in which the float may be dispensed with in which a novel mixing of the gas and air is effected and in which nothing but pure vapor is delivered to the engine when running at normal speeds. Furthermore, by delivering the air through the liquid fuel, the air which is delivered to the engine under normal con-

ditions is washed so that the use of a dust collector is unnecessary.

In first adjusting the device, the needle valve 35 is threaded inwardly until the desired adjustment is reached for idling purposes, it having been found that it is desirable for idling purposes that the tube 24 project into the liquid fuel, the presence of the vapors being of insufficient quantities for idling purposes.

An advantage also of having the tube 24 project into the liquid fuel is that a choking of the engine is eliminated thus avoiding all of the disadvantages which result from choking. This becomes possible as initially, upon starting of the engine, there will be drawn upwardly in the tube 24 sufficient fuel to start the engine and because of the mixture of the fuel with the air which enters through the pipe 57 this fuel will serve the purposes of priming, and be delivered to the engine in a thoroughly vaporized and aerated form. This also prevents a flooding of the engine which is commonly done when a choke is used.

While I have illustrated and described the preferred form of my invention, I do not wish to limit myself to the precise details of structure shown but desire to avail myself of such variations and modifications as may come within the scope of the appended claims.

Having thus described my invention, what I claim as new and desire to secure by Letters Patent is:

1. In a carburetor of the class described, a bowl adapted for the reception of liquid fuel; a conduit communicating with said bowl for delivering fuel thereinto and extending inwardly of said bowl to the normal level of the fuel contained therein; a conduit communicating with the atmosphere and projecting inwardly of said bowl and opening thereto at a position below the normal level of the fuel contained therein; outlet passages communicating with said bowl and positioned above the normal level of the fuel contained therein; and an outlet conduit communicating with said bowl and terminating at a position below the normal level of the fuel contained therein.

2. In a carburetor of the class described, a bowl for the reception of liquid fuel; an outlet conduit communicating therewith and terminating at a position below the normal level of the fuel contained therein; and means communicating with said conduit for delivering air thereto at a position below the normal level of the fuel; and a plurality of outlet passages connecting the interior of said bowl with said outlet conduit above the normal level of the fuel in said bowl.

3. In a carburetor of the class described, a bowl for the reception of liquid fuel; an outlet conduit communicating therewith and terminating at a position below the normal

level of the fuel contained therein; means communicating with said conduit for delivering air thereinto at a position below the normal level of the fuel; a conduit communicating with the atmosphere and projecting inwardly of said bowl and opening thereinto at a position below the normal level of the fuel contained therein; and means for controlling communication of said last named conduit with the atmosphere.

4. In a carburetor of the class described; a bowl for the reception of liquid fuel; an outlet conduit communicating therewith and terminating at a position below the normal level of the fuel contained therein; means communicating with said conduit for delivering air thereinto at a position below the normal level of the fuel, said conduit being in communication with the interior of said bowl above the normal level of the fuel in said bowl.

5. In a carburetor of the class described: a bowl for the reception of liquid fuel; an outlet conduit communicating therewith and terminating at a position below the normal level of the fuel contained therein; means communicating with said conduit for delivering air thereinto at a position below the normal level of the fuel, said conduit being in communication with the interior of said bowl above the normal level of the fuel in said bowl; and means for controlling the amount of air delivered to said conduit through said means communicating therewith.

In testimony whereof I have signed the foregoing specification.
